United States Patent [19]

Wagner

[11] Patent Number: Des. 290,874

[45] Date of Patent: ** Jul. 14, 1987

[54] **OPERATOR CONSOLE FOR
COMPUTERIZED TOMOGRAPHY
SCANNER SYSTEM**

[75] Inventor: **Kenneth E. Wagner**, Chesterland,
Ohio

[73] Assignee: **Technicare, Corporation**, Cleveland,
Ohio

[**] Term: **14 Years**

[21] Appl. No.: **636,540**

[22] Filed: **Aug. 1, 1984**

[52] U.S. Cl. **D24/2; D14/103**

[58] Field of Search **D24/1.1, 2; D14/100,
D14/102, 103; D10/46; 378/4, 8, 11, 12, 17, 21,

[57] **CLAIM**

The ornamental design for an operator console for computerized tomography scanner system, as shown and described.

DESCRIPTION

FIG. 1 is a perspective view of an operator console for computerized tomography scanner system showing my new design;

FIG. 2 is a front elevational view thereof;

FIG. 3 is a side elevational view thereof;

FIG. 4 is a top plan view thereof; and

FIG. 5 is a rear elevational view thereof.

FIG-1

FIG-2

FIG-3

FIG-4

FIG-5
